X-RAY TUBE.

Application filed October 20, 1924. Serial No. 744,549.

This invention relates to vacuum devices and particularly to X-ray tubes especially adapted for dental work.

In the form of X-ray tubes now in use irrespective of the type, it is the practice to support the electrodes thereof from extensions which are usually oppositely disposed. This construction requires separate supports for each electrode, and thereby complicates the method of manufacture.

Another characteristic feature of present-day tubes is that of employing a high vacuum, the degree of vacuum depending upon the particular type of tube. In such tubes employing an incandescent cathode the determining factor as to the degree of vacuum is that the tube shall operate substantially free from gaseous ionization, and other details, such for example as the spacing of the electrodes and the voltage at which the tube is to be operated, are controlled by this factor.

It is an object of our invention to provide an X-ray tube having a greatly simplified construction with respect to prior art tubes.

Another object is the provision of an X-ray tube so constructed that the relation of the electrodes thereof, and the form of mounting therefor, obviates the necessity of having a vacuum as high as that required in other forms of tubes having similar characteristics, i. e., using the same range of operating voltages, etc.

Another object of our invention is to provide an X-ray tube adapted to operate at a relatively high voltage and with a relatively high vacuum therein, but so designed that the vacuum need not be as high as normally required in a pure electron-flow X-ray tube, because of the close spacing of the active faces of the electrodes and the restricted areas around other portions of said electrodes.

Another object of our invention is the provision of an X-ray tube in which the electrodes thereof are so assembled prior to introduction thereof into a bulb, as to comprise a unitary mount, which may be sealed into the bulb after assembly in the same fashion as a lamp mount is sealed into an incandescent electric lamp.

Another object is providing an electrode

assembly which may be supported from one stem of the tube.

A further object of our invention is the provision of an X-ray tube having a single stem supporting the anode and an insulating attachment on said anode for supporting the cathode and properly spacing and insulating it from the anode.

A further object of our invention is the provision of an X-ray tube in which the anode or target is almost entirely enclosed by an insulating member which serves the double purpose of a support for the cathode and means for absorbing stray X-radiation, said insulating member being provided with a focusing device positioned opposite the working face of the anode for focusing electrons from the cathode thereon.

A still further object of our invention is the provision of an X-ray tube in which both cathode and target are supported from a single stem and closely spaced and insulated from each other by means of a refractory insulating member, with a metal absorption screen on the outside of said insulating member for absorbing stray X-radiations and provided with a central aperture for allowing a useful cone of X-rays to emerge therefrom.

An additional object of our invention is the provision of an X-ray tube of improved construction in which an incandescent electron-emitting cathode is provided generating an electron stream which flows to the anode or target substantially along the longitudinal axis of the tube and of the target, impinges on the working face of the target and generates a main beam of X-rays which flows back along the same axis through the center of said incandescent cathode and out of the tube.

Other objects and advantages of the invention will become apparent as the description proceeds.

According to the present invention, a preferred embodiment of our novel form of X-ray tube comprises an evacuated bulb or envelope formed with a main substantially spherical or spheroidal portion and an auxiliary substantially cylindrical extension therefrom. This extension preferably holds the target or anode of the tube and is pro-

vided with a screw-plug, electrically connected to said target, so that the tube may be conveniently connected, disconnected or replaced, for convenient use with auxiliary apparatus, such as a high-voltage transformer, delivering current at from 40,000 to 60,000 volts, with which it is adapted to be used.

The cathode, which is formed as one or 10 more turns of refractory wire or filament, is supported by and spaced from the anode by means of an insulating refractory member which substantially surrounds the anode. As a means for energizing the cathode, leading-in conductors are provided, extending 15 into the tube, preferably through the main portion thereof, substantially opposite to the cylindrical extension in which the anode is supported.

10 The anode or target is preferably formed of copper or other non-refractory metal with an insert of thorium or other refractory metal of high atomic weight, for example, uranium, serving as the focal surface for efficiently generating X-rays. The cathode which is supported close to said thorium insert, is preferably formed of tantalum or other refractory metal, such as tungsten, molybdenum or may be oxide-coated platinum. Inside of the 25 insulating member and adapted to support and space the cathode is a substantially cylindrical focusing device surrounding the cathode.

The focusing device may be provided with 30 a cup-shaped extension toward the target and is preferably formed of insulating material like that forming the support and insulation between the anode and cathode. If the supporting and insulating member is formed 35 of material, such as lavarock, the same may either be made thick enough adjacent the focal surface of the target to absorb substantially all misdirected X-radiation or a metallic absorption screen in the form of a cup, 40 closely fitting the exterior of the insulating support, may be provided. The insulating support, focusing device and absorption screen, if used, are centrally perforated so that a useful cone of X-rays may pass there- 45 through, along the common axis of the tube and anode. The insulating support is preferably formed nearly as large, in diameter, as the cylindrical extension of the bulb so that the space therebetween is restricted to mini- 50 mize ionization.

All parts of the aforementioned electrode assembly, that is the anode or target, the surrounding insulating member, the focusing device and the incandescent cathode support- 60 ed thereby are assembled and formed into a mount, that is, secured to a stem in any desired manner prior to sealing into the bulb. Such a mount may then be sealed into the bulb in the same manner as a lamp mount is inserted 65 into its bulb.

Our invention will be better understood by referring to the accompanying drawing, in which;

Fig. 1 illustrates a preferred form of our X-ray tube, shown partly in longitudinal sec- 70

Fig. 2 shows, in section, a modified form of stem for our tube.

Fig. 3 illustrates still another form of stem for the tube.

Fig. 4 is a drop perspective showing the elements of the electrode assembly;

Fig. 5 is a plan of our focusing and cathode-positioning device with the cathode shown in position; and,

Fig. 6 is a side elevation of the device shown in Fig. 5.

The envelope or bulb 1 of our tube is preferably constructed with a main substantially spherical or spheroidal portion 2 of relatively large radii of curvature and an auxiliary, substantially cylindrical extension 3. This cylindrical extension is preferably provided with a screw-plug 4, adapted to be inserted in a receptacle or socket of a type similar to those in which ordinary large incandescent lamps are operated. Such a receptacle may form part of a casing of an enclosed transformer or any other auxiliary apparatus desired, used in connection with our X-ray tube. Although the main portion 2 of the tube is shown substantially spherical, it may be made substantially cylindrical, like its extension 3, and merely large enough in diameter to avoid undue heating thereof. If 100 cylindrical, its axis should correspond substantially with that of the extension 3 and contained electrodes.

It will be noted that the X-ray tube of the present application is substantially symmetrical about its longitudinal axis. A single stem 5 which supports both electrodes and other interior members in the tube, is provided. On account of this construction, the entire interior structure of the tube may be assembled in proper relation before insertion and sealing into the bulb.

Supported from the stem 5, preferably by means of a split cylindrical, resilient metal sleeve 6, is an anode or target 7, which may be connected to the member 6 in any desirable manner, as by being threaded into a plug 8 thereof, as shown. The plug 8 may be connected to the sleeve 6 in any desired manner, as by pins 9.

The target 7 is provided with a focal insert 10, preferably formed of thorium, preferably threaded and then pressed, to make better thermal contact, or otherwise mechanically connected therein. An insulating supporting and spacing member 11, generally in the form of a hollow cylinder, is provided surrounding the target 7. This member 11, which is preferably formed of lavarock, lavite or soapstone, whose main constituent is mag- 130

nesium silicate, turned to the desired shape and then baked, may be held in position by fitting it over a reduced section 12 of the anode 7, which section is provided with a 5 threaded portion which is then screwed into the end of the member 6, or plug 8 thereof, to thereby rigidly hold both the anode 7 and insulating member 11 in position by engagement of the shouldered portion formed on the 10 target, with the cooperating reduced annular portion of the member 11 which closely fits the reduced portion 12.

Inserted into the free end of the insulating member 11 is a substantially cylindrical focusing device 13, preferably comprising lavarock turned to shape and baked, in the same manner as the supporting member 11. The focusing device 13 is preferably provided with a cup-shaped extension toward the target 20 7, as shown, which may partially enclose the focal area of the target and absorb stray X-rays therefrom. This extension is adapted to snugly fit the end of the lavarock support. The interior of the cup is preferably 25 substantially hemi-spherical. A cylindrical flanged extension 14 is preferably provided on the focusing device. A filamentary cathode 15, preferably formed as a coil of tantalum wire, is supported close to the focal insert 10, 30 by means of the focusing device, as more fully described in connection with Figs. 5 and 6. It is clear, however, that the cathode may be formed of platinum or the like coated with alkaline earth material, or formed of other 35 refractory metal besides tantalum.

Unless the lavarock insulating member 11 and focusing device 13 are made relatively thick, so that stray X-radiation is absorbed thereby, a metal absorption screen 16, preferably 40 formed as a nickel cap, is provided enclosing the end of the insulating support 11, adjacent the focal insert 10 of the target 7. This absorption screen 16 may support the focusing device 13 and be connected to the insulating support 11 in any desired manner. 45

The cathode 15 may be energized by means of leading-in conductors 17 and 18 extending through the bulbous portion of the tube at 19 and 20, substantially opposite to the cylindrical extension 3 and screw-base 4 thereon. The cathode, if of tantalum or other metal having a correspondingly high melting point, may be operated at such a degree of incandescence that no anode material will distill 55 thereto and condense thereon. This will avoid activation of the cathode by distilled thorium from the anode, if thorium for example, is so used, with a consequent increase in emissivity and current through the tube. In 60 this way more uniform operating characteristics are obtained. The target 7 is provided with a leading-in conductor 21, connected thereto in any desired manner, for example, by means of screw 22. The other end of the 65 conductor 21 is electrically connected to the

center contact of the screw-base 4, by means of solder, for example, for introducing the desired current thereto.

In constructing our present form of tube, the insulating support 11 and focusing device 70 13 are preferably formed of lavarock, lavite or soapstone, by turning the same on a lathe, although, as is obvious, other insulating materials such as porcelain, fused quartz, thoria or the like may be used. After turning to 75 shape, these insulating members, if of lavarock, are baked at about 1100° C. This treatment hardens them, eliminates moisture and increases the insulating properties thereof.

The baking operation of the lavarock 80 should be conducted in the air or other oxidizing atmosphere and ordinarily a change in color is effected during the baking operation. After the lavarock members are put into service in the tube or during the treating 85 of the electrodes preparatory to sealing off the tube, care must be taken not to over-heat the lavarock members in the vacuum, because if this is done, a loss in insulating properties 90 is effected. That is, it may be that some reducing gas, such as hydrogen, is left when the bulb is exhausted, or developed during the operation of the tube, so that if the lavarock members become heated beyond a certain point, a change in color takes place with 95 an increase in their conductivity, so that their insulating qualities are seriously impaired.

After the electrodes and elements associated therewith are assembled in proper relation outside of the bulb, they are applied to 100 the stem 5 and inserted bodily into the cylindrical extension 3 thereof and the stem 5 sealed therein to hold them in place. The leading-in conductors 17 and 18, to the filamentary cathode 15, may be threaded through 105 apertures provided at 19 and 20 when the electrode assembly is inserted into the bulb, after which these apertures are sealed, as shown at 19 and 20.

The bulb is exhausted and the electrodes 110 treated in any desired manner to free them from gases and vapors. The tube may then be operated with the filament 15 at incandescence and one of the leading-in conductors 115 therefor grounded, so that the only portion of the tube at high-potential is the anode end or screw-base 4. The desired high-potential is applied between this screw-base and one of the leading-in conductors to the cathode. The electrons liberated at the cathode 15, 120 when the tube is being operated, flow to the closely-spaced focal surface of the insert 10 of the target 7 and generate X-rays thereon. The main body of these X-rays pass back along the axis of the tube, which is also the 125 axis of the anode, through the aperture 23 of the focusing device 13 and metal absorption screen 16, if used, as a useful cone of X-rays.

By means of this construction, a good 130 focus is obtained on the focal surface of the

insert 10 and a large proportion of the X-rays generated pass through the aperture and form a cone of X-rays for the desired purpose.

- 5 Within a very short time after the tube is initially operated, the lavarock focusing device 13 will have acquired a negative potential from electrons impinging thereon and serves to focus the electron stream in a manner as efficiently as if it were a metal focusing device electrically connected to the cathode. Pin-hole photographic pictures of the target taken by means of X-rays during operation of the tube, show very good focusing, in fact as good as that obtained when conducting focusing means are used. When using the absorption screen 16 of nickel or the like, it is found that the lavarock may be made relatively thin and yet substantially 10 all stray X-radiation is efficiently absorbed by the screen.

Three stem constructions and two sealing-in arrangements are illustrated in the drawing and the constructional details thereof are 15 as follows. In Fig. 1 the stem 5 supporting the electrode assembly is open at its inner end and requires two sealing-in operations for completion. That is, before sealing-in, the cylindrical extension 3 of the bulb 1 extends beyond the point at which the stem 5 is connected thereto and is of uniform diameter. When assembling the various parts, the leading-in conductor 21 is sealed through the tube 24 at the press 25. This tube 24 is preferably provided with a slight outward flare at its outer end 26.

- 20 The stem 5 with the electrode assembly thereon, is held in a suitable manner, preferably by means of a split hollow holder, inserted in the extension 3 and the flare 27 of stem 5 sealed thereto at 28. The leading-in conductors 17 and 18, at the time of insertion, are preferably threaded through apertures or tubulation at 19 and 20. That portion of the extension 3 beyond the seal 28 is then heated and drawn to form the tapered portion 29, the outer end of which is sealed to the tube 24 at the flared portion 26. All 25 this may be accomplished before exhausting and before the leading-in conductors 17 and 18 are sealed through the glass at 19 and 20.

- 30 One of these conductors, 17 for example, may then be sealed through the glass and a portion of the tapered part 29 heated while 35 pressure is applied at the aperture for the leading-in conductor 18 to blow a hole at 31 for purposes of exhaust. A suitable exhaust tube is then connected at 31, leading-in conductor 18 for the cathode sealed at 20 and the tube exhausted and tipped off in the usual manner. After this has been accomplished, the screw-base 4, which may be the usual form of "mogul" base, is applied thereover as shown, the leading-in conductor 21 extending through the central electrode 32

thereof and preferably being soldered thereto at 33 as shown.

Although this leading-in conductor is shown connected to the central electrode 32, it is obvious that, if desired, it may be connected to the outer or threaded electrode 34. The space between the screw-base and the tapered portion 29 of the tube is filled with a suitable cement 35, before the base is applied to the bulb.

70 The ends of the leading-in conductors 17 and 18 are brought through and sealed into the bulb forming protuberances 19 and 20, which are subsequently crowned with contact caps 36 and 37 cemented thereon and 75 provided with central apertures through which the leading-in conductors 17 and 18 are threaded and soldered thereto.

75 The modified construction illustrated in Fig. 2 avoids the necessity of a seal corresponding to that between the tapered portion 29 and tube 24. In this modification a stem 43, of a type similar to that used on lamps of the "tipless" variety, is preferably employed. That is, the stem 43 has the leading-in conductor 21 sealed therethrough at 44 so that it is closed, rather than open, at its inner end. It is however, provided with an exhaust tube 45 preferably extending from 80 near the inner end thereof, to beyond the 85 other end of the stem.

80 In order to seal-off a tube with this type of construction, it is merely necessary to form the single seal at 46 between the flare 47 on the stem 43 and the extension 3 of the 90 tube. This makes it possible to make the electrode assembly complete, connect it in place on the stem and seal the stem in one operation into the bulb at 46, after which it is merely necessary to exhaust the bulb 95 through the exhaust tube 45 and tip-off at 48. Of course, it is also necessary to seal the leading-in conductors 17 and 18 of the cathode through the glass, the same as for the first 100 modification as illustrated in Fig. 1.

100 As in Fig. 1, the screw-base 4 of Fig. 2, is applied in the same manner, but it will be noted that it fits down over the main portion of the extension 3 to a greater extent than as shown in Fig. 1 and makes it unnecessary 115 to use as much cement as with the form shown in Fig. 1. The leading-in conductor 21 extends through the central electrode 32 as in Fig. 1 and is soldered thereto in the same manner, although it may be connected to the 120 outer electrode, if desired.

125 The split sleeve 6 for holding the electrode assembly on the stem may be of the same construction as illustrated in Fig. 1. That is, it may be provided with a longitudinal slot 49 and a transverse slot 50 joining therewith, so that the free wings of the sleeve formed, serve to resiliently hold the assembly in position on the stem. Although the 130 cathode assembly may be merely frictionally

held in position, it is preferable to lock the same securely on the stem. For that purpose, a bayonet slot or slots 51 may be provided in the sleeve and a lug or lugs 52 sealed onto the stem 5 or 43 or both. The cathode assembly may be securely locked in place by inserting the split sleeve over the stem with the bayonet slot 51 engaging the lug 52 until the inner transverse portion of the slot is reached, after which the sleeve is twisted on the stem to the position shown in Fig. 2, when the sleeve is securely locked in position, as will be understood.

Fig. 3 shows a modified form of stem 43' for the tube, which is like the stem 43 shown in Fig. 2, except that the exhaust tube 45' joins directly with the press 53, through which the leading-in conductor 21 extends, instead of being sealed into the stem independently of the press. Such a stem is adapted for manufacture on a machine for making stems for the usual type of "tipless" incandescent electric lamps. The press is formed with the aid of air pressure, applied to the exhaust tube 45' to blow a hole through the press into the bulb, so the press 53 contains a bulbular cavity 53' between the exhaust tube 45' and the hole to the interior of the bulb.

Fig. 4 is a drop perspective to illustrate the order of assembly of the various electrode elements. From this it will be clear that the anode 7 is inserted into the insulator 11 and screwed into the plug 8 of the split sleeve 6 which is attached to the stem 5. The focusing device 13 with the incandescent cathode 15 in place therein, is then inserted in the insulator 11 and the nickel cap 16 is then inserted thereover and held in place by screws or the like.

Figs. 5 and 6 illustrate, in detail, the insulating focusing device 13 and the incandescent cathode 15 in position therein. As clearly shown in these figures, the focusing device 13 preferably comprises three main portions; (1) a central cylindrical portion 54; (2) an end cup-shaped portion 55 and (3) a flanged portion 14 at the opposite end.

The flanged portion 14 is provided with apertures 56, 58, through which the leads 17 and 18 extend in a direction parallel with the axis of the tube, after which they are bent at right angles and extend inwardly toward the axis to connect with the centrally-held incandescent cathode 15. To provide for the insertion of said cathode 15 and for holding it securely in position, the focusing device is slotted at 57, as shown, in Fig. 5, said slot preferably extending through the cup-shaped portion 55 and part of the cylindrical portion 54. The slot is preferably deeper at one side than the other, as shown, so that the coiled filament is supported properly when in the bottom of the slot, the difference in depth corresponding to the pitch of the coil. The incandescent cathode 15 and its connected leading-in conductors may then be positioned in

said slot with the free ends of the leading-in conductors extending through apertures 56 and 58. As supplemental means for spacing and positioning the incandescent cathode 15 the inner end of the insulator 11 is provided with slots 59 and 60 engaging the leading-in conductor elbows 61 and 62.

By means of the foregoing arrangement, the incandescent filament is accurately positioned with respect to the cooperating focal portion 10 of the target, motion being prevented in one direction, after assembly, by the slots 59 and 60 and in the other direction by the inner end of the slot 57. After the focusing device is positioned with its cathode in place, the shield 16, if used, is inserted thereover and held in place in any desired manner, for example, by means of screws 63 and 64 extending through the shield 16, the insulating member 11 and into the focusing device 13 to hold them rigidly together in position. Apertures 65 and 66, larger than the apertures 56 and 58 in the focusing device, are preferably provided in the shield, so that short circuiting between the leading-in conductors 17 and 18 is obviated.

Upon again referring to Fig. 1, it will be noted that in accordance with the foregoing description, the insulating and supporting member 11 is formed of such a size that it fits the cylindrical extension 3 of the bulb fairly close. That is, the area 67, between the glass of the bulb and the insulating member 11, is quite restricted. The distance between the cathode 15 and the focal insert 10 of the target 7 is likewise relatively small. That is, it preferably ranges between 8 and 15 millimeters. An advantage secured by such a construction, is that the vacuum in the bulb 1 need not be as high as ordinarily required in an ordinary type of X-ray tube adapted to operate on a voltage, corresponding to that for which the present tube is designed, and still avoid a substantial amount of gaseous ionization. The vacuum, however, should be high enough so that the mean free path of electrons in the bulb is great compared to the distance between the active faces of the electrodes, to avoid substantial gaseous ionization therebetween, as will be understood.

Gaseous ionization between the cathode 15 and the outer portion of the target 7 and supporting sleeve 6 is minimized and substantially eliminated by the restricted portion 67 between the bulb 1 and the insulating member 11 and the restricted area between the target 7 and the insulating member 11, it being apparent from the drawing that the insulating member 11 is designed to closely surround the target 7.

As an example of what a tube of the foregoing construction will accomplish, it may be stated that in operating such a tube on alternating current of 50,000 volts maximum with 5 milliamperes of current therethrough,

an exposure of from 1½ to 3 seconds only, is required for radiographs of teeth, with the patient positioned at a distance of 6 inches from the tube. Longer exposures are necessary, of course, if the patient is positioned at a greater distance, according to the law of inverse squares. For example, an exposure four times as long is required, if the patient is positioned one foot away from the tube.

From this it is obvious that a great advantage is secured with a tube according to the present construction where the patients may be positioned very close, because of the absence of danger from shock at the cathode end of the tube. One of the leads to the cathode may be grounded so that the other is at a potential merely high enough to cause the heating current therefor to flow through it. For this reason, the patient may get as close as is necessary to the cathode end of the tube, in the path of the useful cone of X-rays emerging from the aperture in the focusing device and X-ray screen, if used.

As previously mentioned, very good focusing is secured with a tube of this type so that good definition is attained even when the object radiographed is positioned very close to the tube. Because of the absence of high-tension leads in that part of the tube adjacent the object radiographed, very close positioning is permissible without danger. Inasmuch as the length of exposure may be very much shortened by close spacing of the object with respect to the tube, in accordance with the law aforementioned, it will be seen that a tube of the present construction has a great advantage over the usual type of X-ray tube where close positioning is impossible.

If it is desired to run the tube on varying voltages and currents so that care must be taken to avoid overheating the target and particularly the copper or non-refractory portion thereof, it is preferable to have one or more apertures 68 in the insulating member 11, so that the degree of heating of the target 7 may be observed, while in operation. As an alternative or auxiliary, an instrument for registering the degree of heating of the target, may be used.

Although a preferred embodiment of our invention is illustrated, it is obvious that modifications may be made therein, without departing from the spirit and scope of the invention, as defined by the appended claims.

What is claimed is:

1. An X-ray device comprising an evacuated envelope provided with a target and a stem supporting the target, an insulating member surrounding said target and an incandescent filament supported by said insulating member.

2. An X-ray device comprising an evacuated envelope enclosing an anode and a cathode, a focusing device surrounding the cath-

ode and an insulating support extending from the anode and holding said focusing device in position.

3. An X-ray device comprising an evacuated envelope provided with a single stem 70 supporting an anode therein, an insulating member attached to said anode and spacing and supporting an electron-emitting cathode, a focusing device surrounding said cathode and an absorption screen surrounding said 75 focusing device, said insulating support, focusing device and absorption screen being provided with axially arranged concentric apertures for allowing X-radiation to pass out of the tube.

4. In an X-ray tube, an anode and an electron-emitting cathode supported from the anode.

5. In an X-ray tube, an anode and an electron-emitting cathode supported from the 85 anode and spaced with respect thereto, by means of an insulating member.

6. An X-ray device comprising a plurality of electrodes supported from a single stem, and an auxiliary tube in the stem for exhausting the device.

7. An X-ray device comprising an enclosing envelope including a stem portion, an anode or target mounted thereon, an insulating and spacing member supported on said target and an incandescent cathode supported by means of said insulating member and spaced in given relation to the target.

8. An X-ray device comprising an evacuated envelope enclosing an anode and a co-operating electron-emitting cathode, a non-conducting focusing device surrounding the cathode and provided with an aperture for allowing X-rays generated on the target to pass out of the tube along the axis of the 100 electron stream.

9. In a high-voltage electrical device, an anode, an electron-emitting cathode and an insulating focusing device surrounding the cathode.

10. An electrode assembly for an X-ray device comprising a split sleeve formed of resilient material and adapted for application to the stem of an enclosing envelope, a refractory insulating and spacing member, an 115 anode member threaded to the split sleeve and extending through a portion of the insulating member and provided with a shoulder engaging said insulating member, whereby when the anode is threaded into the sleeve 120 it rigidly maintains said three members in alignment and in given spaced relation, and means in the opposite end of the insulating member for supporting an incandescent cathode in proper relation with respect to 125 the target.

11. An electrode assembly for an X-ray device comprising a resilient sleeve adapted for engagement with a substantially cylindrical stem of an enclosing envelope, said 130

5 sleeve being provided with a threaded plug portion in one end thereof, an anode provided with a threaded extension engaging said threaded plug portion and a substantially cylindrical insulating member through which a portion of the anode extends and which is held to said sleeve member by the engagement of a shouldered portion of the anode therewith, when the same is threaded 10 into the plug portion of the sleeve, said insulating member supporting an insulating focusing device at its opposite end, and an incandescent cathode maintained in position by said device.

15 12. An electrode assembly for an X-ray device comprising a resilient sleeve adapted for engagement with a substantially cylindrical stem of an enclosing envelope, said sleeve being provided with a threaded plug portion in one end thereof, an anode provided with a threaded extension engaging said plug portion and a substantially cylindrical insulating member through which a portion of the anode extends and which is held to said sleeve member by the engagement of a shouldered portion of the anode therewith, when the same is threaded into the plug portion of the sleeve, said insulating member supporting an insulating focusing 20 device at its opposite end, an incandescent cathode maintained in position by said device and a shield member extending over the focusing device, attached to the end of the insulating member and provided with a central aperture whereby a useful cone of 25 X-rays is permitted to pass therethrough and stray X-radiation absorbed.

30 13. An electrode assembly for an X-ray device comprising a stem, a split resilient sleeve engaging said stem, an anode and surrounding insulating member rigidly connected to said split sleeve by means of a threaded engagement and a cooperating incandescent cathode accurately positioned with respect to said anode whereby the whole assembly 35 may be completed before the same is introduced and sealed into an enclosing envelope.

35 14. An electrode assembly for an X-ray device comprising an anode, a cooperating incandescent cathode and supporting means therefor between said anode and cathode, means for supporting said assembled electrodes comprising a split resilient sleeve adapted for application to a stem of an enclosing envelope and means for locking said assembly in position on the stem comprising a lug on the stem and a bayonet slot on the sleeve adapted for interlocking engagement with said lug.

40 15. An electrode assembly for an X-ray device comprising an anode or target, an insulating member of laverock rigidly connected thereto and substantially surrounding the same, and a cathode supported by means of said insulating member.

45 16. In an X-ray device, an enclosing envelope provided with a stem, a sleeve supported thereby, an anode or target supported by said sleeve and holding in place a substantially cylindrical insulating member, said insulating member surrounding said target, bolted to the sleeve by the threaded engagement of the target therewith and having attached thereto a focusing device with a slotted portion, and an incandescent cathode held in the slotted portion whereby the cathode is spaced and accurately positioned with respect to the anode or target, for the production of X-rays thereon.

50 17. In an X-ray device, an enclosing envelope provided with a stem, a split sleeve supported thereon by resilient frictional engagement, an anode or target supported by means of threaded engagement with said sleeve and holding in place a substantially cylindrical insulating member, said insulating member surrounding said target, bolted to the split sleeve by the threaded engagement of the target therewith and having attached thereto a focusing device with a slotted portion, and an incandescent cathode held in the slotted portion whereby the cathode is spaced and accurately positioned with respect to the anode or target, for the production of X-rays thereon.

55 18. In an X-ray device, a target comprising a body of non-refractory metal into which is threaded and pressed a focal insert of a refractory metal of high atomic weight.

60 19. In an X-ray device, a target comprising a body of copper into which is threaded and pressed a focal insert of thorium.

65 20. In an X-ray tube, an X-ray shield surrounding the cathode and focal portion of the target and electrically independent of both.

70 21. In an X-ray tube, a single electrode supporting stem, a metal X-ray shield surrounding the cathode and focal portion of the target and supported from said stem.

75 22. An X-ray device comprising an evacuated bulb with a substantially cylindrical extension therefrom, an anode supported in said extension and closely surrounded by an insulator supporting a cooperating incandescent cathode in close relation to the anode, the bulb being evacuated to such a degree only, that the mean free path of electrons is great compared to the spacing of the electrodes, said insulating member being large enough to restrict the area between it and the surrounding extension of the bulb, so that gaseous ionization is substantially absent when the tube is in operation.

80 23. The method of making an X-ray device comprising connecting an anode to a stem while supporting an insulating element on the stem by means of said anode and supporting an incandescent cathode in proper relation with respect to said anode by means of

said insulating element, all of said operations being performed prior to inserting into a bulb.

24. The method of making an X-ray device comprising supporting a target on a stem, supporting an insulating member by means of said target, supporting a holding means for an incandescent filamentary

cathode from said insulating means and sealing said stem and supported members into a bulb.

In testimony whereof, we have hereunto subscribed our names this 18th day of October, 1924.

CLAYTON TRIDLE ULREY.
HARRY DE FOREST MADDEN.
